UNITED STATES PATENT OFFICE

2,169,562

DRAWER OF A VERTICAL TYPE FOR
INDEXING AND CLASSIFYING

Luigi Lombardini, Turin, Italy

Application January 25, 1937, Serial No. 122,177
In Italy January 27, 1936

2 Claims. (Cl. 129—16)

The object of the present invention is the introduction of improvements in drawers, of a vertical type, for indexing and classifying made already known in a United States Patent No. 1,918,765 and a previous Italian patent by the same petitioner under No. 279,387 and Italian patent of Addition No. 303,030 relating thereto.

Under the said main patent and patent of addition relating thereto, the drawer for indexing contains a certain number of special distancing partitions which are connected in a detachable manner, by means of suitable devices, with the bottom of the drawer and in their higher part lean against each other by means of special supports which are applied to the lateral, or top, ends of each distancing-partition. As the projection of the said supports is practically equal to the distance between the distancing-partitions at the spot where they are connected with the bottom 15 of the drawer, it follows that the said partitions are parallel and form as many interchangeable compartments of a constant and comparatively small capacity.

The greater length of the top part of the drawer in relation to the lower part where the distancing-partitions are connected allows of the latter leaning forward and backward so as to form wherever desired an angle of aperture which facilitates the removal or the placing of documents, or their 20 examination.

The above has the object of sectioning, or subdividing,—as already mentioned—the whole volume of the index file in so many compartments, of a fixed capacity, comparatively a small one, and whose partitions, while supporting each other, support also each its own contents of cards or documents, keeping them always in a normal position and distributing the friction among the respective distancing-partitions.

In order that the invention referred to in the said Italian patents may work efficiently, it is necessary that from the beginning each drawer be filled up with as many distancing-partitions as it can bear; because each of them must serve as a support for the next one. This device finds its best application whenever it is a question of classifying elements (cards) of a uniform thickness, particularly thin ones, which require to be sub-divided as much as possible, with the possibility of rapid displacements (interchangeability) of the compartments formed by the distancing-partitions.

In the present case, instead of a classification of elements having an unequal and comparatively greater thickness (heavy cards, files), and where

an easy interchangeability among the various compartments is not strictly necessary, it is useful to be able to sub-divide the volume of the drawer (index) in such a number of compartments as may be gradually required,—comparatively larger ones,—even if of different capacities, but always in a parallel manner.

The improvements forming the object of this invention allow of a complete attainment of the above results, as appears better from the specification which follows:

In the drawers, object of the present, the distancing elements of the partitions, instead of being borne by the partitions themselves are borne by the drawer's sides and bottom.

The annexed drawing illustrates, as an example without restrictions, a chosen form of execution of the invention. In the said drawing, in which the same indications of reference apply to the same parts:

Fig. 1 is a vertical section through the drawer forming the object of the invention;

Fig. 2 is a partial view, in transverse section, showing how a divisional element, or diaphragm, is connected with the corresponding lateral distancing-element of the index-drawer and with the distancing slot and respective central guide at the bottom of the drawer;

Fig. 3 is a partial view, in transverse section, along a lateral distancing-element of the drawer and the respective checking and gliding channel guide;

Fig. 4 illustrates, in perspective, the type of lateral distancing-element considered in Figs. 1, 2 and 3;

Fig. 5 is a view, in perspective, illustrating a part of the bottom and a lateral wall of a drawer bearing distancing elements of the type referred to in Fig. 6;

Figs. 6 and 7 illustrate respectively, in perspective, some chosen types of distancing elements.

As appears from the drawing, to each of the side walls 1 of the indexing drawer is appropriately fixed a proper guide, or channel 2, disposed as is shown particularly in Figs. 1 and 5.

In the said guides, or channels 2, (one for each wall), are inserted the distancing elements of the devised shape, Figs. 3, 4 and 5, in a smaller number, however, than that of the said elements which could be contained in the guides, in order to allow of their gliding along the said guides for the purposes mentioned hereinafter.

The said distancing elements are constituted by a base 6, of an appropriate shape, for instance having a square, rectangular, or circular 55

section, bearing a projection (3 or 4 or 5), of various forms and dimension. These projections serve for supporting, and therefore guiding, the lateral and higher projection 11 of divisional elements 7.

In accordance with the type of distancing element adopted, lateral projections 11 of partition 7 lean on projections 4 or 5 of bases 6, or are set in slot 12 of projection 3. In the case of projection 3, in order that slot 12 may accompany ends 11 of the partition when inclining forward or backward,—as will be seen hereinafter,—and take up its various positions (Fig. 1) the said projection is mounted so as to turn on its base—Fig. 3.

The bottom of the drawer is provided with several slots 8₁, 8₂ . . . 8₁₄, or the like, in a number corresponding to that of the distancing elements, and such slots are adapted to receive and withhold, in the manner known, by means of central pin 9, (or other similar device) partitions 7.

The distance between slots 8₁, 8₂ . . . 8₁₄, must be equal to that between the respective distancing elements contained in a number equal to that of the said slots.

The total length of guides 2 being greater than that formed by slots 8 of the bottom of the drawer allows the distancing elements to glide forward and backward dragging with them the respective partitions 7 by means of their ends 11 and causing them to pivot around their points of connection with slots 8 so as to form, where desired, a certain angle of aperture for the easy removal, or placing, of documents or of their examination.

When preparing the indexing drawer and by degrees, as it is desired to subdivide it into more compartments, the partition (or the partitions) 7 are introduced into the proper slot 8. At the same time, ends 11 of partition 7 are set in the space formed between projections 4 or 5 of the distancing elements in relation to slot 8 in the case of the type illustrated by Figs. 5, 6 and 7, or in slots 12 of distancing elements in relation to the corresponding slot 8 in the case of the type illustrated by Figs. 1, 2, 3 and 4.

The greater length of guides 2 in respect to the total length of the drawer bottom allows of the easy displacement forward and backward of the distancing elements contained therein, while buffers 10 made of rubber, or of a similar substance, 5 deaden their shocks against the front or back of the indexing drawer.

At the same time, they drag or push in their movements partitions 7 by means of their edges 11 leaning properly on projections 4 or 5—or set in slot 12 of projections 3—of the respective distancing elements. The said partitions 7 will thus assume the desired inclination forward or backward remaining, however, for the objects aimed at by the invention, always parallel with 15 similarly positioned partitions.

The forms of execution illustrated and described are susceptible of all such variations and modifications of construction as come within the scope of this invention, as shown by the following claims.

What I claim and desire to secure by Letters Patent is:

1. In a filing drawer having a series of partitions, the combination of a longitudinal guide channel lying in a vertical plane, distancing elements slidable in said channel, said distancing elements comprising blocks which are engaged along their sides, top and bottom by the guide channel so as to permit sliding movement only 30 of said blocks, and abutments projecting horizontally from a side of said blocks for engagement with the side walls of the drawer partitions, said abutments being pivotally supported by the blocks for rotation about a horizontal axis at 35 right angles to the side of the blocks.

2. In a filing drawer having a series of partitions, the combination of guide means, distancing elements slidable in said guide means, said distancing elements comprising blocks which are 40 engaged along their sides, top and bottom by the guide means so as to permit sliding movement of said blocks only, and slotted abutments projecting horizontally from a side of said blocks, said slots receiving the side walls of the drawer partitions.

LUIGI LOMBARDINI.
